DESIGN FOR A LACE

Leon Birnbaum, New York, N. Y.

Application July 15, 1936, Serial No. 63,852

Term of patent 3½ years

To all whom it may concern:

Be it known that I, Leon Birnbaum, a citizen of the United States of America, residing in city of New York, county of New York and State of New York, have invented a new, original, and ornamental Design for a Lace of which the following is a specification, reference being had to the accompanying drawing, forming part thereof.

The figure in the drawing is a plan view of a lace embodying my new design.

The design unit is contained between the broken vertical lines, which unit is repeated in regular succession, as indicated by the extensions beyond the unit boundaries.

I claim:

The ornamental design for a lace substantially as shown and described.

LEON BIRNBAUM.
